(57) **CLAIM**

The ornamental design for a shoe, as shown and described.

DESCRIPTION

FIG. 1 is a side view of a shoe showing my new design;

FIG. 2 is a front perspective view thereof;

FIG. 3 is an opposite side front perspective view thereof;

FIG. 4 is an opposite side view thereof; and,

FIG. 5 is a top view thereof.

The broken lines immediately adjacent to the interior of the solid lines and the unshaded areas within each form no part of the claimed design. The broken lines and unshaded areas depicting the remainder of the shoe form no part of the claimed design.

1 Claim, 5 Drawing Sheets(56)
